UNITED STATES PATENT OFFICE.

JAMES R. STEELE, OF OWEGO, NEW YORK.

RAIL ANCHOR.

Application filed May 20, 1925. Serial No. 31,474.

To all whom it may concern:

Be it known that I, JAMES R. STEELE, a citizen of the United States, and a resident of Owego, in the county of Tioga and State 5 of New York, have invented a new and useful Rail Anchor, of which the following is a specification.

The invention relates to rail-anchors, or anticreepers as they are also called, and 10 more particularly to one-piece rail-anchors. The object is to provide a rail-anchor of this class which requires only a short drive transversely of the rail to obtain a grip of exceptional force, and which will not back off 15 under vibration.

In the accompanying drawings illustrating an embodiment of the invention:

Fig. 1 is a rear elevation of the device on a rail in section, and against a portion of a 20 tie, the anchor being in the position in which it is first put on, before any driving;

Fig. 2 is a similar view showing the anchor partly driven on the rail;

Fig. 3 is a similar view showing the 25 anchor fully driven, or practically so;

Fig. 4 is an end view of the anchor on the rail, a portion of which is seen in elevation, a portion of the tie being in section;

Fig. 5 is a vertical sectional view taken on 30 the line 5—5 of Fig. 3;

Fig. 6 is an elevation of the rail-anchor off the rail;

Fig. 7 is a vertical cross-section on the line 7—7 of Fig. 6; and

Fig. 8 is a plan view of the anchor.

The rail is marked A and the tie against which the anchor 2 abuts is marked B. The anchor is made by punching from a plate of 40 .70-.80 carbon steel, that is to say, material in the tool steel class. The plates are punched at a temperature of about 2000° F., and are air cooled by allowing them to cool individually in the air, the result being a stiff plate-girder yoke.

The punching operation removes the upper interior part of the plate, forming a cut-out to receive the rail base, the yoke thus formed comprising a transverse under-rail portion 3 and integral long and short jaws 45 or hooks 4, 5 at the opposite ends. These jaws lie in the plane of the plate, except that the long jaw 4 has a stiff arm 6 bent therefrom to extend generally lengthwise of the top of the rail base. The punching 50 operation forms a draft angle or bevel 7 on

the edge including the upper side of the under-rail portion and the under sides of the jaws, which draft angle is utilized in the manner hereinafter described. It will be observed that the arm 6 extends away from the 60 flare of the bevels, that is to say from the side of the plate where the corners formed by the draft are acute, as shown in Fig. 7.

The lines of the under sides of the jaws 4 and 5 are designed so as to bear full upon 65 the sloping top surfaces of the rail base flanges when the anchor is applied, at which time the stiff arm 6 also bears upon the top of one of the flanges so as to tilt the yoke away from the arm in the manner seen in 70 Figs. 4 and 5. For purposes of manufacture it is desirable to bend the arm 6 at less than a right angle to the jaw 4, with the result that it lies diagonally, extending somewhat up the slope of the rail, but this 75 is not essential. A wide recess under the jaw 4 permits the yoke to be hooked laterally onto the rail base, in preliminary application, in a manner which has long been 80 familiar in anticreepers.

It will be noted that the relation of the arm 6 to the bevel 7 is such that the tilting of the yoke caused by the arm further tilts the bevel 7 of the under-rail portion so as to present the acute edge corner 8 more 85 sharply to the bottom face of the rail, while the beveled under surfaces of the jaws 4, 5 are tilted over so that they lie substantially flat upon the top of the rail flanges (see Fig. 5).

The parts are so proportioned that when the anchor is put on in preliminary position, the long jaw 4 and its arm are well up on one rail flange, while the short jaw 5, which is at the driving end of the yoke, is 95 not engaged over the other flange, its under surface then being somewhat below the line of slope of this rail flange, as will be seen in Fig. 1. The rounded or beveled lower forward corner 9 of this jaw presented to the 100 somewhat rounded upper edge corner of the rail flange permits the short jaw to mount up on the rail flange when this end of the anchor is struck with force.

The longitudinal line of the top of the 105 under-rail portion in the half, more or less, adjacent the jaw 5 at the driving end is a straight tangent, this tangent being marked 10. In the other half of the yoke the top of the under-rail part slopes downward for 110

clearance to the bottom of the recess under the jaw 4, this slope being marked 11.

The inclined under side of the jaw 5 at the driving end of the anchor and the top 5 surface 10 of the under-rail part are so spaced and in such converging relation as to wedge over the edge of the rail flange, gripping the top and bottom thereof; and the construction is such, further, that the 10 jaws are out of line, that is to say when the yoke is driven until the line 10 bottoms against the rail, the jaw 4 and its arm 6 would, if the metal were at rest, fall slightly below the top of the rail flange. In other 15 words, in the condition of Fig. 2 the yoke is strained. The measurable distortion is slight, and may be considered to be distributed in the left-hand half of the yoke in this view, but owing to the nature of the 20 material the stress is very great. Now, if the yoke is driven farther in a straight line, to the position of Fig. 3, for example, the jaw 4, with its arm, rides down the slope of the rail flange, and the strain is in conse- 25 quence largely relieved, there still remaining at the end, however, a heavy stress in the metal which causes this jaw and arm to grip powerfully downward on the top of the flange. It will, therefore, be perceived that 30 the anchor is driven through a condition of momentary excessive strain in one part of the anchor, namely the forward part of the anchor away from the end which is driven, and that further driving relieves this excess- 35 strain without impairing the holding, while at the same time increasing the wedging action at the driving end of the yoke. The combined effect is to produce a very tight, unrelaxing grip, not dependent on the 40 use of spring steel, and not affected by vibration or weather conditions, and also to make it impossible for the anchor when properly applied to work backward and lose its grip, since the anchor can not move to 45 the right in Fig. 3 without causing the jaw 4 and arm 6 to ride up a slope and restore the excess strain previously relieved. When the anchor is fully driven and seated, the 50 end of the tangent 10 remote from the driving end of the yoke is past the center of the rail, in other words to the left of such center in Fig. 3.

Abrasion, particularly of the acute corner edge 8 of the tangent 10 contributes to the 55 operation of the anchor. This edge is partly swaged or flattened down in the driving, substantially as is represented in Figs. 3 and 5, which not only permits driving after the parts have become initially wedged, but 60 produces a considerable extent of intimate binding contact between the yoke and the bottom of the rail. As a further means to promote abrasion or swaging, the under side of the jaw 5 may be somewhat relieved, 65 as at 12, behind its bearing nose, so that this

nose may abrade as it is driven in strong bearing contact with the top of the rail flange.

The arm 6 performs the function which has been referred to in connection with the 70 bevels 7. It also braces the anchor against wabbling about an axis transverse to the rail. The anchor is preferably applied so that the arm extends forward in the direction of traffic, as shown, tilting the yoke 75 at the top away from the tie, but the operation of the anchor does not require this position, and the anchor can also be put on in the reverse manner.

The anchor can be taken off and re-applied, the design allowing for successive 80 small amounts of abrasion and affording a capacity for being repeatedly stressed without exceeding the elastic limit.

While the preferred embodiment of the 85 invention has been described in detail, it will be understood that the invention is not limited to the precise form.

I claim:

1. A one-piece rail-anchor comprising an 90 under-rail part to bear against the bottom of the rail and long and short end jaws to engage over the rail flanges, with a wide clearance recess beneath the long jaw, the rail-anchor being designed to be applied by driving it transversely of the rail by force applied at the end of the yoke having the short jaw, the portion of said under-rail part which bears against the bottom of the rail being a straight tangent which extends from about the middle of the width of the rail toward the driving end to bottom against the rail as the short jaw is forced up the slope of its rail flange, substantially as 95 set forth.

2. A one-piece rail-anchor consisting of a 100 punching from a plate of material such as .70-.80 carbon steel forming a stiff-girder yoke comprising an under-rail part to bear against the bottom of the rail and long and short end jaws to engage over the rail flanges, with a wide clearance recess beneath the long jaw, the rail-anchor being designed to be applied by driving it transversely of the rail by force applied at the end of the yoke 105 having the short jaw, the portion of said under-rail part which bears against the bottom of the rail being a tangent which extends from about the middle of the width of the rail toward the driving end to bottom against the rail as the short jaw is forced up the slope of its rail flange, substantially as 110 set forth.

3. A transversely-driven one-piece rail- 115 anchor comprising an under-rail part and integral end jaws adapted to engage over the rail base flanges, the top of the under-rail part being formed with a tangent extending toward the jaw at the driving end 120 of the yoke, said tangent and jaw adapted 125

to wedge on the rail base, the relations being such that the part of the anchor comprising the other jaw is strained when said tangent bottoms against the rail, after which further driving of the anchor swages one part of the anchor on the rail flange and relieves excess strain in the other part of the anchor.

4. A transversely-driven one-piece stiff-girder rail-anchor made of a vertical plate having an under-rail portion and long and short jaws at the opposite ends to engage over the rail flanges, the plate having a wide clearance recess under the long jaw, the upper edge of the under-rail portion in the half adjacent the short jaw being a tangent and in the other half dropping downward to said recess, the short jaw and the tangent being adapted to wedge on the rail flange, and the long jaw having a stiff arm bent therefrom in the general direction of the length of the other rail flange, substantially as set forth.

5. A transversely-driven one-piece rail-anchor made of a punching from a plate of material such as .70-.80 carbon steel to form an under-rail portion and integral long and short end jaws, the upper edge of the under-rail portion and the under edges of the jaws having a draft angle, and an arm bent from the long jaw in the general direction of the length of the rail flange, substantially as set forth.

6. A one-piece rail anchor comprising a yoke designed to be driven transversely of the rail, said yoke comprising an under-rail portion provided with a tangent abrading edge, a short jaw at the driving end

adapted to mount up on one rail flange causing the tangent abrading edge to bottom against the rail, and a long jaw at the opposite end, the part of the yoke bearing the long jaw being adapted to be strained at such time and to have its external strain relieved by further driving on the rail.

7. A one-piece rail-anchor comprising a yoke of material such as .70-.80 carbon steel adapted to be driven transversely of the rail and comprising a short jaw and an under-rail tangent together forming wedging means in the driving half of the yoke adapted to embrace one rail flange with a wedging grip, the other half of the yoke being recessed so as to be free of the rail and having long jaw means adapted to be strained by bearing on top of the other rail flange.

8. A one-piece rail-anchor consisting of a punching from a flat plate forming a stiff-girder yoke having an under-rail portion and long and short jaws and adapted to be driven transversely of the rail, said short jaw and the under-rail portion extending beneath it forming wedging means having an abrading edge adapted to be forced into a wedging grip with one of the rail flanges, the other part of the yoke being recessed so as to be free of the bottom of the rail and having long overhanging means adapted to be strained by bearing on top of the other flange as the yoke is driven and to have its external strain relieved as the driving end of the yoke is forced to its final wedging grip.

JAMES R. STEELE.
